UNITED STATES PATENT OFFICE.

SIDNEY HOLE, OF HASOCKS, ENGLAND.

CLOSURE MEANS FOR MILK CHURNS.

Application filed June 21, 1922. Serial No. 569,850.

To all whom it may concern:

Be it known that I, SIDNEY HOLE, a subject of the King of England, residing at Hassocks, Sussex, England, have invented 5 certain new and useful Improvements in Closure Means for Milk Churns, of which the following is a specification.

This invention is for improvements in or relating to closure means for milk churns.

10 As is well known, the closure means commonly employed for milk churns frequently works loose so that the closing lid becomes detached from the churn, and few, if any, of them are fluid-tight.

15 According to the present invention, the closure means for the milk churn comprises a lid which co-operates with the mouth portion of the vessel to be closed, one of these parts being a male element and the other a 20 female element, characterized by the male element having in its engaging surface two parallel circumferential grooves, the female element having in its engaging surface a groove which registers with that groove 25 which is second from the entering end of the male element, and a ring of elastic material such as rubber, preferably of circular cross-section placed in the first groove of said male element, the said ring and grooved 30 parts being of such dimensions that when the lid is forced into position, the ring will roll from the first groove into the second groove where it will engage the groove in the female element and serve to key the two 35 parts together.

Preferably, the entering portion of the lid has a flange below the grooves nearest the entering end which is of a larger diameter than the part situated between the 40 grooves to prevent displacement of the rubber ring from the said end when the lid is being removed, and a single groove is provided in the mouth of the churn which registers, when the lid is in the closing position, with that groove farthest from the entering end of the lid.

45 A further feature of this invention consists in making provision for the insertion of levers between the mouth of the churn and an overhanging portion of the lid, for example the usual outwardly directed flange, so that the lid can be levered off the churn.

Another feature of the invention consists 50 in providing closure means of the kind set forth above characterized by one or more concealed spring-catches carried by the lid

or within the mouth of the vessel, each catch having a shouldered cam-portion, by the other element, say the mouth of the vessel, having a circumferential lip so situated and 60 dimensioned that as the lid is pushed into position the said lip will have sliding engagement with the cam-portions of the catches until it becomes locked behind the shouldered portions thereof, and by recesses 65 provided in the lid or vessel or both, whereby one or more implements can be introduced to thrust back the spring-catches when the lid is to be released.

In the accompanying drawings which illustrate one method of carrying out this invention as applied to a milk churn,

Figure 1 is a central vertical section through the top of a churn, and half of the lid is also shown in central vertical section, 75 the parts being in the position they occupy prior to the closure being effected;

Figure 2 shows the same parts in section as in Figure 1, but in the closed position;

Figure 3 is a vertical section through one 80 side of a churn and its lid, illustrating on a larger scale a detail shown in Figures 1 and 2, and

Figure 4 is a face view of the side portion 85 of the lid carrying a locking device.

Like reference letters indicate like parts throughout the drawings.

The usual churn body is indicated at A, and the mouth portion B is flared somewhat after the usual manner. At the smaller portion 90 of this flared mouth a groove B¹ is provided, and above the groove is a lip B² which restricts the throughway of the mouth to approximately the same diameter as that of the part B³ which lies below the 95 groove.

The lid C is of tapered construction, and has a central well, and in this respect is similar to churn lids at present employed, but the part C¹ is made approximately 100 parallel and contains two circumferential grooves C² and C³ respectively. The groove C³ is toward what may be called the leading end of the lid, as it is that end which enters first when the lid is applied, and beyond the 105 groove is a flange C⁴ which is made as large in diameter as possible to prevent accidental detachment of a rubber ring D which operates in the grooves C², C³.

When the lid is about to be applied, the 110 parts take the position shown in Figure 1, that is the ring D lies in the lower groove

C³ nearest the leading end of the lid, and when the lid is laid loosely in position the ring will bear against the lip B². If now the lid is forcibly driven down the ring D will be distorted and will roll between the engaging surfaces of the lid and the mouth of the churn so that it will pass out of the groove C³ into the groove C², and at the same time will roll over the lip B² into the 10 groove B¹ of the churn. In this position it will serve as a key to hold the lid firmly in position, and as it is sufficiently large in diameter to rather more than fill the grooves C² and B¹, it will be under compression, and 15 will thus make a fluid-tight joint between the lid and the mouth of the churn.

The lid has an outwardly turned flange E which bears against the top of the churn and thus limits the degree of downward 20 movement, and for many purposes the ring affords all the necessary security for the lid, in fact it has been found that the churn can be lifted by the handle F without any displacing action of the ring D taking place 25 to release the lid. To enable the lid to be withdrawn, lateral recesses E¹ are provided in its edge at two opposite points, so that short levers can be inserted therein and the lid can be prised up sufficiently to roll the 30 rubber ring D back into the groove C³ and out of the groove B¹. The parts will then again be in the position shown in Figure 1 and the lid can be lifted free of the churn. The flange C⁴ is intended to prevent accidental displacement of the rubber ring 35 from the lid when the lid is off the churn.

If further locking of the lid is required, the mouth of the churn may be provided with an internal lip G which is continuous 40 round the mouth, and the lid may carry spring-catches in the form of locking tongues H for co-operation with this lip. It will be seen that when the lid is in the closing position as shown in Figure 2, shoulders H¹ on the spring tongues lie beneath 45 the lip G and thus positively lock the lid against removal but the tongues are placed opposite the recesses E¹ and extend beyond the lip G into these recesses so that when the 50 levers for prising up the lid are introduced, the tongues can be pressed back to free the shoulders H¹ from the lip G, and then the lid can be prised up as already described.

What I claim as my invention and desire 55 to secure by Letters Patent is:

1. In a milk churn of the character described, the combination of a body portion in the form of a can, a lid having a cylindrical wall adapted to enter with play into 60 the mouth of the body portion, and having two parallel circumferential grooves separated by a rib, whereof the first groove is nearer to and the second groove is more remote from the entering-end of the lid, 65 the said mouth of the can having an in-

ternal peripheral groove arranged to register with the said second groove when the lid is in its closed position, and an elastic closure ring seated in the first groove in the lid prior to applying the lid and movable over 70 said rib into the second groove and adapted to enter, in the closed position of the lid, said internal groove, the said ring and grooves being of such dimensions that when the lid is forced into its closed position, the ring will roll from the first groove in the lid into the second where it will engage said internal groove and serve to key the lid in its closed position, said lid further having below the first groove a flange of a diameter 80 substantially larger than that of said rib, which flange serves to prevent displacement of the closure ring from off the bottom of the lid when the can is being opened and when the lid is off. 85

2. In a receptacle, the combination of an element constituting the body portion thereof, a second element constituting a lid having a cylindrical wall adapted to enter with play into the mouth of the body portion and having two parallel circumferential grooves separated by a rib whereof the first groove is nearer to and the second groove is more remote from the entering-end of the lid, the said mouth of the can having an internal 90 peripheral groove arranged to register with the said second groove when the lid is in its closing position, and an elastic closure ring seated in the first groove in the lid prior to applying the lid, and movable over 95 said rib into the second groove and adapted to enter, in the closing position of the lid, into said internal groove, the said ring and grooves being of such dimensions that when the lid is forced into its closing position, the ring will roll from the first groove in the lid into the second where it will engage said internal groove and serve to key the lid in its closing position, said lid having below the first groove a second rib of a diameter 100 larger than that of said rib, which second rib serves to prevent displacement of the closure ring from off the bottom of the lid when the can is being opened, one of said 105 elements having a continuous peripheral lip, and a spring-catch mounted on the other of said elements and arranged automatically to engage said lip in the closing position of the lid, and one of said elements having a recess 110 opposite to the said catch for the insertion of an implement for disengaging the catch from the said lip. 115

3. In a receptacle, the combination of an element constituting the body portion thereof, a second element constituting a lid having a cylindrical wall adapted to enter with play into the mouth of body portion, and having two parallel circumferential grooves separated by a rib, whereof the first groove is nearer to and the second groove is more 120

remote from the entering-end of the lid, the said mouth of the can having an internal peripheral groove arranged to register with the said second groove when the lid is in its 5 closing position, and an elastic closure ring seated in the first groove in the lid prior to applying the lid, and movable over said rib into the second groove and adapted to enter, in the closing position of the lid, into said 10 internal groove, the said ring and grooves being of such dimensions that when the lid is forced into its closing position, the ring will roll from the first groove in the lid into the second where it will engage said internal 15 groove and serve to key the lid in its closing position, said lid having below the first groove a second rib of a diameter larger than that of the first said rib, which second rib serves to prevent displacement of the 20 closure ring from off the bottom of the lid when the can is being opened, the mouth of said body portion having a continuous internal peripheral lip, spring-catches, each having a shouldered cam-portion, carried by 25 the lid and arranged automatically to engage said lip with the cam-ports when the lid is pushed into its closing position and lock the lid against removal, one of said elements having recesses, one opposite each 30 spring-catch, for the insertion of an implement for disengaging the catches from said lip.

4. In a milk churn of the character described, the combination of a vessel having

a mouth portion in the form of a cone, a lid 35 having a cylindrical wall adapted to lie concentrically with said mouth portion, which said mouth portion and lid constitute one a male element and the other a female element 40 cooperating therewith, which male element has two parallel circumferential grooves separated by a rib, whereof the first groove is nearer to and the second groove is more remote from the entering-end of the male element, said female element having an internal 45 peripheral channel in the form of a groove arranged to register with said second groove when the lid is in its closed position, and an elastic closure ring seated in the first groove in the male element prior to applying the lid 50 and movable over said rib into the second groove and adapted to enter, in the closed position of the lid, said channel, the said ring and grooves being of such dimensions that when the lid is forced into its closed 55 position, the ring will roll from the first groove in the male element into the second where it will engage said channel and serve to key the lid in its closed position, said male element further having at the 60 entering side of the first groove a flange of a diameter larger than said rib for preventing displacement of the closure ring from off the entering-end of the male element when the can is being opened and when the 65 lid is off.

In testimony whereof I affix my signature.
SIDNEY HOLE.
